UNITED STATES PATENT OFFICE.

CHRISTIAN HEILRATH, OF SACRAMENTO, CALIFORNIA.

TRACE-HOLDER.

SPECIFICATION forming part of Letters Patent No. 784,214, dated March 7, 1905.

Application filed July 19, 1904. Serial No. 217,289.

To all whom it may concern:

Be it known that I, CHRISTIAN HEILRATH, a citizen of the United States, residing at Sacramento, in the county of Sacramento and State of California, have invented a new and useful Trace-Holder, of which the following is a specification.

The invention relates to improvements in trace-holders.

10 The object of the present invention is to improve the construction of trace-holders and to provide a simple, inexpensive, and efficient device adapted to be applied to a whiffletree having the usual trace-receiving tongue and eye without necessitating any alteration in the construction of the whiffletree.

15 A further object of the invention is to provide a trace-holder adapted to be attached to a whiffletree by the trace-receiving tongue and capable of securely retaining a trace thereon and of enabling a trace to be quickly attached to and removed from a whiffletree.

With these and other objects in view the invention consists in the construction and novel 20 combination and arrangement of parts herein-after fully described, illustrated in the accompanying drawings, and pointed out in the claims hereto appended, it being understood that various changes in the form, proportion, 25 size, and minor details of construction within the scope of the claims may be resorted to without departing from the spirit or sacrificing any of the advantages of the invention.

In the drawings, Figure 1 is a perspective 30 view of a trace-holder constructed in accordance with this invention and shown applied to a whiffletree. Fig. 2 is a longitudinal sectional view of the same. Fig. 3 is a detail perspective view of the attachment plate or support.

Like numerals of reference designate corresponding parts in all the figures of the drawings.

1 designates an attachment plate or support consisting of a disk or ring having a central opening 2 to receive the threaded shank 3 of a trace-receiving tongue 4 of a whiffletree 5. The whiffletree is provided with the usual sleeve or ferrule 6, and the attachment 35 plate or support is interposed between the

end of the whiffletree and a shoulder 7 of the trace-receiving tongue, as clearly illustrated in Fig. 2 of the drawings, whereby the attachment plate or support is firmly clamped in position. The attachment plate or support is provided at the top with a lug 8, to which is pivoted a trace-holding hook 9. The trace-holding hook 9 has its inner end 10 bifurcated to receive the lug 8, and the sides of the bifurcated end and the lug are pierced by the pivot 11. 55 The outer end of the trace-holding hook bears against the tongue adjacent to the eye 12, and it is held in such position by a coiled spring 13, which is arranged within a longitudinal socket or opening 14 of the trace-holding hook. 60 The spring is provided with an engaging member consisting of a head or block 15, having a shank fitting against the lug 8, which is tapered to present inner and outer inclined faces. The engaging member of the spring is adapted 65 when the hook is swung to its open position to engage the inner inclined face of the lug for holding the hook in such position. The means for holding the hook in its opened and closed positions does not constitute a portion of the 70 present invention, as it is claimed in an application filed by me of even date herewith. The lug extends inward over the sleeve and it affords a firm support for the hook. 75

It will be seen that the device is exceedingly 80 simple and inexpensive in construction, that it possesses great strength and durability, and that it is adapted to be applied to whiffletrees of the ordinary construction without necessitating any alteration in the same by means of 85 the trace-receiving tongue.

Having thus fully described my invention, what I claim as new, and desire to secure by Letters Patent, is—

1. The combination with a whiffletree, and 90 a trace-receiving tongue extending into the whiffletree, of a support fitted against the end of the whiffletree and secured to the same by the tongue, and a trace-holding hook hinged to the support and co-operating with the tongue. 95

2. The combination with a whiffletree, and 100 a tongue having a shoulder and provided with a shank extending into the whiffletree, of a support consisting of a plate having an opening to receive the shank and interposed be-

tween the shoulder of the tongue and the end of the whiffletree, said plate being also provided with a projecting lug, and a trace-holding hook pivoted to the lug and coöperating with the tongue.

3. The combination with a whiffletree, of a support consisting of a plate fitted against the end of the whiffletree, a trace-receiving tongue piercing the plate and clamping the same

against the whiffletree, and a hook pivoted to the support and coöperating with the tongue.

In testimony that I claim the foregoing as my own I have hereto affixed my signature in the presence of two witnesses.

CHRISTIAN HEILRATH.

Witnesses:

EDWARD A. MEISTER,
FRANK VAN ALSTINE.
